UNITED STATES PATENT OFFICE.

WILLIAM PARKER HAMMOND, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-RACK.

1,270,817.

Specification of Letters Patent.

Patented July 2, 1918.

Application filed May 1, 1914. Serial No. 835,729.

To all whom it may concern:

Be it known that I, WILLIAM P. HAMMOND, a citizen of the United States, residing at Boston, in the county of Suffolk and 5 State of Massachusetts, have invented certain Improvements in Shoe-Racks, of which the following description, in connection with the accompanying drawings, is a specification, like reference characters on the 10 drawings indicating like parts in the several figures.

This invention relates to shoe racks of the type used in shoe factories to hold the shoes between the successive manufacturing operations on them and to transport the shoes 15 from one part of the factory to another.

While some type of a shoe rack is a necessary part of the equipment of every shoe factory, the use of these racks is always 20 attended with a certain amount of damage to the shoes. This damage is sometimes caused by the fact that some part of the rack with which the shoe comes in contact is sufficiently rough to abrade the shoe, particularly if the workman uses unnecessary 25 force in placing the shoe in the rack or in taking it therefrom. Another very common cause of rack damage to shoes is the fact that certain types of rack in very common use, as for instance that shown in the 30 Saunders Patent No. 440,439, granted November 11, 1890, is so constructed that the shoes are allowed to tip or slide into contact with each other. A part of one shoe striking another may not cause any damage at 35 certain stages of the manufacture of the shoe, particularly if heavy stock is used in the shoes, but there is great danger of damage if such contact occurs while the lasting 40 tacks are projecting from the shoes or if the shoes are made of light and delicate stocks. It is the primary object of the present invention to devise a construction of shoe rack which will eliminate much of the 45 trouble above described.

The invention will be readily understood from the following description, reference being made to the accompanying drawings, in which—

50 Figure 1 is a view in side elevation of a rack embodying the invention; and

Fig. 2 is an angular view showing the details of construction of the shelves used in the rack shown in Fig. 1.

The frame of the rack shown in the drawings is constructed substantially in accordance with the disclosure in my Patent No. 1,100,072, June 16, 1914. Briefly stated, this frame comprises a base frame 2 and end frames 4 secured to opposite ends of the base frame by means of removable bolts. Diagonal brace links 6 connect the respective end frames with the base frame and support the end frames in their upright positions, and a tie rod 8, extending longitudinally of the 55 rack connects the upper ends of the end frames and serves to spring them toward each other and to give the frame additional 60 rigidity.

Any desired number of shelves may be 70 supported in the frame, each shelf preferably having two end members extending transversely of the rack and mounted removably on small brackets 10 carried by the end frames. Each of these shelves comprises a toe supporting bar 12 secured to 75 said end members and extending longitudinally of the rack; and a series of pairs of shoe supporting pins 14 projecting laterally from said bar, the members of each 80 pair being inclined slightly toward each other at their outer ends, as clearly shown in the drawings. Each shelf is designed to support a plurality of shoes in their inverted positions, each pair of pins being arranged to support the body of a shoe between them, in the manner indicated in Fig. 2, with the toe portion of the shoe resting on the bar 12. The shelf construction so far described is substantially like that shown 85 in the Saunders patent above designated.

In order to prevent the shoes from coming in contact with each other, a series of substantially vertical spacing pins 16 is provided on the bar 12, these pins being 90 located, respectively, between the positions occupied by adjacent shoes, or in other words, between the adjacent pairs of shoe supporting pins 14. This relationship is clearly shown in the drawings, from which 100 it will be evident that each pair of spacing pins prevents a shoe positioned between them from tipping or sliding into contact with either of the adjacent shoes. By limiting the movement of the shoe the spacing 105 pins also reduce the rubbing of the shoe against the pins 14 with the consequent liability of marring the upper leather.

In order to support the toe portions of the shoes out of contact with the bar 12 and thus prevent these parts of the shoes from being soiled or injured by a contact with the bar, a deep groove is formed longitudinally of the bar in its upper surface, and a strip 18 of felt or other yielding non-abrasive material is inserted in this groove, the strip being of such dimensions that its edge projects well above the upper surface of the bar. The bar, with this strip of material, forms the rest for the toe portions of the shoes; but the strip of felt 18 holds the toe portions of the shoes out of contact with the bar. The strip of felt preferably is secured in the groove by applying a coat of glue to the bottom edge of the strip before it is inserted in the groove. This arrangement makes it convenient to remove the felt when it becomes soiled by running a chisel or similar tool along the bottom of the groove under the felt and thus lifting the strip out of the groove. The pins 16 preferably are located between the strip 18 of felt and the side of the bar from which the supports 14 project so that the pins 16 will engage the wide or ball portions of the shoes and thus limit their movements more effectually than if the pins were located so as to engage only the narrower parts of the shoes.

As a further precaution against soiling or injuring the uppers of the shoes, the pins 16 may each be covered with a sleeve

20, Fig. 2, of cloth, paper or other suitable material, and the shoe supporting pins 14 likewise may be covered with a similar sleeve 22, Fig. 2. These sleeves may be removed and new ones substituted therefor whenever they became soiled.

Having thus described my invention, what I claim as new and desire to secure by Letters Patent of the United States is:

In a shoe rack, the combination with a toe rest comprising a toe supporting bar having a groove in its upper surface extending longitudinally thereof and a strip of yielding non-abrasive material in said groove with its edge projecting above the surface of said bar, of a series of pairs of pins projecting laterally from said rest, each pair of pins being constructed and arranged to support a shoe between them with the shoe in its inverted position and its toe on said strip of material, and a series of spacing pins projecting upwardly from said toe rest and located between said strip of material and said series of shoe supporting pins, said spacing pins being positioned, respectively, between the adjacent pairs of said shoe supporting pins.

In testimony whereof I have signed my name to this specification in the presence of two subscribing witnesses.

WILLIAM PARKER HAMMOND.
